UNITED STATES PATENT OFFICE.

ARTHUR H. McCARREL, OF WASHINGTON, DISTRICT OF COLUMBIA

LOOM.

Application filed June 13, 1923. Serial No. 645,179.

To all whom it may concern:

Be it known that I, ARTHUR H. McCARREL, a citizen of the United States, residing at Washington, in the District of Columbia, have invented a new and useful Loom, of which the following is a specification.

This invention relates to a loom which is particularly adapted for weaving a special fabric to be used in the manufacture of soft or semi-soft turned-down collars.

The general object of the invention is to construct a loom, which will enable those skilled in the art of weaving, to produce suitable fabrics of a texture, design, construction, type and detail out of which a soft or semi-soft folding collar can be manufactured with economy of labor; the collars being of a turned-down or folding type, each made from one blank stamped out of a special fabric and capable of being completed in a workman-like manner, and with a desirable finish as to details.

It is a further object of the invention to construct a loom on which a fabric may be woven which is firm, smooth and level, which will be free from any internal stresses, which will readily admit of easy and economic handling and manufacturing in all subsequent processes of boiling, bleaching, drying and calendering preparatory to the stamping of the blanks for the collars, and in which, due to the construction and method of weaving, the filling picks will all be beaten up by means of a curved reed, so that they extend across the fabric in parallel arcs, the curvature of which remains constant.

According to one method, narrow fabrics, in which the collar blanks run lengthwise, are woven on narrow-ware looms with a conical take-up motion. Such fabrics assume a spiral shape when doffed from the looms, and this causes extra care, trouble, waste and expense in handling during the processes of bleaching, calendering, drying and finishing. The weave of such narrow-ware fabrics on the narrow-ware looms with the conical take-up motion is expensive; it is almost impossible to distribute the tension uniformly across the width of the fabric; and the processes of bleaching and finishing produce strains in such fabric which are apt to change the set of the curved folding line that is woven in such fabric for the manufacture of collars.

In weaving the fabric, it is my intention

to weave it in suitable widths, so that the collar blanks may be cut transversely of the fabric, with the warp threads running transversely of the collar across the folding line. For the manufacture of a standard number 15 collar a fabric about eighteen inches in width is required.

With a loom constructed according to my invention, the picks are all beaten up by the curved reed so that they run across the fabric in arcs which conform to the natural shape of the collar, after the latter is folded, and a narrow strip consisting of a predetermined number of picks deposited under a special weave is formed in each collar blank to constitute the folding line.

A more complete exposition of the inherent advantages of this specially woven fabric, and the method of manufacturing collars from the same will be found in my co-pending applications filed June 13, 1923, Serial Numbers 645,178 and 645,180.

In the weaving of this fabric either a standard loom with a fly-shuttle pick motion, or one with a shuttle positively actuated by rack and pinion may be used. In either case a chain motion or dobby head is used. Whatever type of loom is used, the structure thereof will be modified, in accordance with the present invention, so that the curved reed may be used, and if found necessary or desirable, a curved lay may be used.

In the weaving of ordinary cloth the warp threads run lengthwise thereof and the filling is beaten up by a straight reed disposed at right angles to the length of the cloth, so that each pick of filling extends across the width of the cloth at right angles to the warp threads. In weaving with the present invention having a curved reed, each pick of filling when beaten up and permanently set in the cloth, forms a curve across the width of cloth, the nature and extent of the curve depending upon the shape of the reed used. In the weaving of this special fabric suitable for the manufacture of collars, a reed about twenty-four inches long should be used, and should be curved to form an arc, with a middle ordinate of about one inch, the center of the circle forming the arc being in front or in rear of the loom.

In the standard fly-shuttle loom, the inside surfaces of the rear faces of the shuttle boxes on each side of the loom, and the front surfaces of the reed when in place

are all in line and form one vertical plane; and the upper surfaces of the shuttle box plates or lay ends and of the race plate are all in line and form one horizontal plane; so that in such a loom when adjusted the axes of the shuttle boxes coincide, and the boxes aline with each other and with the reed and the lay. In such a loom, so adjusted, it is possible to operate with a shuttle and without any warp 10 yarn in the loom. The shuttle traverses from box to box across the lay and parallel with the reed. In a narrow loom properly adjusted with the above described curved 15 reed, the curve is so slight, the radius of the circle forming the same being about six feet, that it is also possible to operate the loom with the shuttle traversing properly from box to box to distribute each pick of 20 filling and beat the same up properly to the fell of the cloth.

In adapting my invention to a standard loom, therefore, a straight lay may be used, with the rabbet for receiving the lower edge 25 of the reed, and the groove in the reed cap for receiving the upper edge so curved as to form the desired curve in the reed. It may, however, in weaving wider fabrics, be desirable also to provide a curved lay.

30 All of the above described modifications in the loom will be more clearly understood from the following detailed description taken in connection with the accompanying drawings, in which

35 Figure 1 is a plan view of a portion of a loom having a curved reed and straight lay.

Figure 2 is a similar view of a loom in 40 which the lay as well as the reed is curved.

Figure 3 is a plan view of the reed and lay.

Figure 4 is a front elevation of the reed.

Figure 5 is a vertical section taken transversely through the lay, reed and reed cap.

45 Figure 6 is a plan view of a portion of fabric which may be woven on the improved loom.

In the loom shown in Figure 1, the lay 21 is oscillated in the usual manner by the 50 crank arms 11, and crank shaft 12. At each end of the lay is a shuttle box 13, and the shuttle 14 is reciprocated back and forth to carry the filling thread through the shed by means of pickers 15 slidably mounted on guide rods 16, and actuated by the picker sticks 17. The warp threads 18 55 are actuated by the harness 19 and held in the usual manner between the wires 20 of the reed, shown in Figures 3, 4 and 5. The parts thus far described are of standard 60 construction.

In carrying out my invention the lay 21 has its rear edge curved on the line 22, and the rabbet 23 formed in the rear upper portion 65 of the lay for receiving the lower rib

24 of the reed is similarly curved for the present purpose. This curve is in the shape of an arc of about twelve feet radius, preferably with the center of the arc in front of the loom. The cleat 25 for retaining the 70 rib 24 in the rabbet is similarly curved. The reed cap 26 is also provided with a curved groove 27 opposite to the rabbet 23 for receiving the upper rib 28 of the reed. Thus, it will be seen, that when the reed 75 is secured to the lay, the wires 20 will form the elements of a cylindrical surface, substantially perpendicular to the fabric to be woven, and the picks as they are beaten up to the fell of the cloth, as shown at 29, 80 will extend across the fabric in a series of parallel curves, while the warp threads 18 are all straight and run lengthwise of the fabric.

In the event that the fabric to be woven 85 is too wide for the shuttle to traverse without guidance from the reed, then a lay may be constructed, as shown in Figure 2, in which the axes of the shuttle boxes 30 form portions of an arc of a circle, which is concentric with the arc of the front surface 90 of the curved reed, but distant from the same a distance equal to one-half the width of the shuttle. In this case, the pickers 31 and the picker sticks 32 travel in slightly 95 curved paths which are determined by the guide rods 33, and the shuttle is guided along the curved inner face of the reed, the surface of the rear side of the shuttle being humored to fit the front surface of the 100 shuttle box back.

In the application of the present invention to the weaving of fabric specially designed for the manufacture of one-piece turned-down collars, the fabric will be so 105 woven as to produce a succession of duplicate patterns 34, each of sufficient dimensions and proper shape for the production of one stamped collar blank for the manufacture of one collar. By means of the chain 110 head or dobby head of the loom in combination with the multiplier motion and the standard methods of shifting from one dobby pattern to another, all of which are supplied on looms of this type, as will be 115 clearly understood by those skilled in the art of weaving, each pattern is woven so as to include a predetermined number of picks, as represented at 35, which will form a narrow strip having a distinctive weave, or a 120 change in filling, or both, adapted to form the folding line of the collar which is marked out and cut from the fabric, and on the line indicated at 36.

The principles which govern the weaving 125 of these patterns, and the method of manufacturing collars therefrom, are more fully explained in my co-pending applications above referred to, but since the fabric and the collars produced therefrom form no part 130

of the invention herein claimed, no further description here will be necessary.

With the above described modification in the construction of the well known parts of a standard loom, a loom is set up in which the curved reed can function, as above described, the shuttle can traverse to and fro along the predetermined line of travel parallel with the front surface of the reed, which is curved, successively bottoming and binding in the boxes at each end of each stroke; the pick motion can operate; and all the movements of the parts can take place normally without hindrance or binding. In all the parts mentioned above as being curved, such curves consist of arcs having a common center, but having radii of different lengths.

It will also be readily understood that the curved reed with the opposed curved channels in the lay and reed cap may be used in connection with a positively actuated shuttle, as well as in a loom of the fly shuttle type.

The specific modifications necessary to adapt the loom to the purpose described and as herein illustrated and described may, of course, be varied to accommodate the size and shape of the particular article which is to be manufactured, as long as such variations mark no material departure from the salient features of the invention as herein claimed.

What is claimed is:

1. In a loom, the combination with a reed, of a lay and reed cap having curved means for securing the upper and lower ribs of the reed so that the dents of the reed develop a substantially cylindrical surface, a shuttle, and means for propelling the same in an arcuate path formed by said cylindrical surface.

2. In a loom, the combination with a reed, of a lay, a reed cap having arcuate channels for receiving and holding the upper and lower ribs of the reed so that the dents there-

of form elements of a cylindrical surface, a shuttle, and means for propelling the shuttle along the curved path formed by said cylindrical surface.

3. In a loom, the combination with a reed, of a lay, a reed cap, means for securing the reed in said cap so that the dents of the reed form elements of a cylindrical surface whose axis is in front of the loom, a shuttle, and means for propelling the shuttle along the curved path formed by said cylindrical surface.

4. In a loom, the combination of a curved lay, curved reed, shuttle boxes and shuttle, in which the front surface of the reed, the front surfaces of the shuttle box backs and the rear face of the shuttle each form a part of the same arcuate surface, and means for initially propelling the shuttle in the direction of a line which is tangent to said arcuate surface.

5. In a loom, the combination of a curved lay having a curved reed, and shuttle boxes in which the front surfaces of the backs are curved to form a continuation of the curved front surface of the reed, said curve being concave toward the front of the loom, and a shuttle traversing from box to box following said curve, the sides of the shuttle being similarly curved so as to traverse without binding.

6. In a loom, a lay curved horizontally with its concave surface toward the front of the loom, a reed similarly curved, curved shuttle boxes whose axes are concentric with the front surface of the reed, and a shuttle whose rear surface is similarly curved so that the front surface of the reed, the front surfaces of the shuttle box backs and the rear surface of the shuttle form parts of the same curve.

In testimony that I claim the foregoing as my own I have hereto affixed my signature.

ARTHUR H. McCARREL.
